UNITED STATES PATENT OFFICE.

HENRY PEARSON, OF SPRINGFIELD, MASSACHUSETTS, ASSIGNOR, BY MESNE ASSIGNMENTS, TO THE AMERICAN PALACE CAR COMPANY, OF PORTLAND, MAINE, A CORPORATION OF MAINE.

RAILWAY-SLEEPING-CAR AND OTHER BERTH SECTION.

No. 924,823.

Specification of Letters Patent.

Patented June 15, 1909.

Application filed May 8, 1907. Serial No. 372,530.

To all whom it may concern:

Be it known that I, HENRY PEARSON, citizen of the United States of America, and residing at Springfield, in the county of 5 Hampden and State of Massachusetts, have invented certain new and useful Improvements in the Construction of Railway-Sleeping-Car and other Berth Sections, of which the following is a specification, reference being 10 had therein to the accompanying drawing.

My invention relates to improvements in such railway cars, ships and dwellings as comprise sleeping-berths; pockets for receiving the berths when they are not in use; trap-doors that either, when horizontal, cover the pockets and form part of the floor; or, being raised, form end partitions for berth-sections and support berth-raising and lowering 15 devices in operative position; the pockets containing actuating mechanisms for the berth-raising and lowering devices which severally operate to raise or lower either or both the lower berth and upper berth of a 20 section, out of or into the pocket of that section.

Among the objects of my invention are to so improve constructions of the foregoing type that they shall practically endure the 25 severe strains of use (especially in railway-cars and ships) and secure privacy between different sections and between the upper and lower berths of each section; and to produce a construction by means of which a berth or berths, when raised into position for sleeping, shall be so rigidly locked as to obviate all danger of their becoming loosened in that position under strain; and to position the raised trap-doors and berths in relation 30 one to the other and to the side wall of the car, cabin or room in such wise that they will not rattle and so interfere with the slumber of the sleeper. I accomplish these and other objects by the novel means referred to in the claims; but, in order to explain the operation and importance of the features which are herein new with me, I show many old parts heretofore invented by me, some of which are shown in U. S. Letters Patent No. 534,756 of February 26, 35 1895, and No. 549,391 of November 5, 1895, each granted to me.

In the drawings, illustrating one form of railway passenger-car embodying my improvements in the best mode now known to

me, Figure 1 is a side elevation of a car containing my invention. This view shows the drop of the car between the trucks and below the floor line, in which drop the berth-receiving pockets are constructed; Fig. 2 is a view partly in transverse section but mainly in perspective of a portion of the inside of the car and shows parts of the car occupied by chairs which, being removed, permit trap-doors, forming part of the floor and also covering the berth-receiving pockets, to be raised to divide the car into sections. This view shows one section with the lower berth and upper berth in position for sleeping use, and shows a part of another section with the upper berth raised into position for sleeping use as a "lower." Fig. 3 is a view partly in vertical elevation and partly in section looking toward an inner side wall of the car; shows both berths of a section in position for sleeping use between the raised trap-doors of the berth-receiving pocket of that section. This view also shows other features of construction hereinafter pointed out. The lower part of this figure, below the berth, is taken 40 on a line longitudinally of the car so as to cut through the end walls and floor sections of a berth-receiving pocket, the section line corresponding to line 3—3 of Fig. 6. The view is partly in section (at the left-hand end portion of the lower berth and in the thereto adjacent part of the vertical trap-door) at a line corresponding approximately to 3—3 of Fig. 2. This view is also partly in section (at the upper ends of two adjacent vertical trap-doors) at a line corresponding to 3^a—3^a of Fig. 6. Fig. 4 is a view partly in transverse section at line 4—4 of Fig. 3 and partly in elevation and shows the upper berth in position of use as an upper and one 45 of its end flaps raised to form an upwardly extending partition above the upper end of an upright trap-door. Fig. 5 is a view partly in plan and partly in section at line 5—5 of Fig. 4, and shows the bottom of the upper berth, and also the upper side of a side-folding berth-flap on the wall or inner side of the upper berth, and also actuating means for said flap. Fig. 6 is a view partly in elevation and partly 50 in transverse section of the car-body at a line corresponding to line 6—6 of Fig. 2. This view shows a trap-door in vertical position with berth-raising and lowering devices on its inner side; shows the upper and lower 55 100 105 110

berths in the pocket; mechanism in the bottom portion of the pocket, underneath the berths, for actuating the berth-raising and lowering devices; and a crank-operated safety-device for operating said actuating mechanism. Fig. 7 is a view partly in transverse section at a line corresponding to line 7—7 of Fig. 3 and partly in vertical elevation, and shows the lower berth and thereto attached boot-board in position for use. It also shows a part of a berth-locking flap raised into vertical position; and shows a trap-door hinged at an end of a berth-receiving pocket. Fig. 8 shows partly in section at line 8—8 of Fig. 9, and partly in elevation, a mechanism for locking an end of the berth to a raised trap-door, this mechanism being operated by movement of a berth-locking flap hinged to the berth. Fig. 9 is a view partly in section at line 9—9 of Fig. 7, and partly in vertical elevation, and shows a part of the berth-locking flap of the berth and a side view of the berth-locking mechanism. Fig. 10 is a perspective, skeletonized view in the nature of a diagram, and illustrates the preferred form of the berth-raising and lowering devices, and independent actuating mechanism thereof. Fig. 11 is a top plan view of the superimposed winding drums for actuating the berth-raising and lowering devices and shows a part of the latter. This view is partly in section at line 11—11 of Fig. 6. Fig. 12 is a view partly in section at line 12—12 of Fig. 13, of the "duplex winding-drum" so-called; that is, the independent superimposed drums for actuating the berth-raising and lowering devices. Fig. 13 is a top plan view (parts being broken away for greater clearness) of said duplex winding-drum and adjacent parts. The view is partly in section at line 13—13 of Fig. 12. Fig. 14 is a vertical sectional view at a line corresponding to 14—14 of Fig. 6, of a safety-device for operating the actuating mechanism of the berth-raising and lowering devices. This view shows the device in uncoupled position for operating the winding drums. Fig. 15 is a sectional view of the upper portion of the device shown in Fig. 14 and shows the device in coupled condition. Fig. 15^a is a transverse section at line 15^a 15^a of Fig. 15, and shows, in top plan view, the coupling members of the safety-device. Fig. 15^b is a view showing my improved formation of the opposed ends of the teeth of the coupling members. Fig. 16 is a sectional detail of the upper end portions of two adjacent trap-doors (of two adjacent sections) at a line 16—16 of Fig. 17 (nearly corresponding to line x—x of Fig. 2) showing in elevation, an abutment having bolt-receiving recesses, whereby the trap-doors are prevented from being raised past their proper upright position; are locked in position; and are positioned apart for reception of a portable, vertical partition-

forming strip. Fig. 17 is a side elevation of the inner side of an upright trap-door, parts thereof being broken away to show door-locking bolts in locking engagement with the abutment shown in Fig. 16, and to show means whereby the trap-door locking-bolt may be actuated by a key. Fig. 18 is a transverse sectional view, at line 15—15 of Fig. 16, and shows the locking-bolts of two adjacent trap-doors in locking engagement with the abutment; springs carried by the trap-doors to engage with the abutments and prevent rattling; and a partition-receiving space between the trap-doors, with part of a therein contained vertical partition. Fig. 19 is a vertical sectional view, at line 19—19 of Fig. 2, of a trap-door and therewith locked upper berth-flap, and shows the locking device therefor, partly in elevation and partly in section. Fig. 20 is a front view; and Fig. 21 a partial side, and partial sectional, elevation of the anti-rattling curtain-rod lock.

Figs. 10—15, inclusive, are taken from the device of my said Patent No. 549,391 and show parts which of and by themselves form no part of my present improvements, which, however, involve the use of the devices illustrated in Figs. 10—15, inclusive, or of some other suitable berth-raising and lowering apparatus, actuating mechanism therefor, and safety devices for operating such actuating mechanism. Several forms of such requisite apparatus have been proposed, some of which have been chimerical while others may have been practically useful, although I do not know such to be the case. The apparatus shown herein for use in connection with the raising and lowering of the berths has been tested out in actual practice; has been found to withstand the strains and shocks of actual use; and is therefore indicated herein for the better guidance of those who wish to make use of my present improvements.

While my invention is susceptible of use even in dwelling-houses or apartments, it is peculiarly adapted for use in railway passenger-cars and in ship-cabins, where economy of space is desirable, and whenever and wherever it is desired to have a room readily convertible from a chair compartment to a sleeping compartment or vice versa. I herein describe my invention in connection with a passenger railway-car, it being understood that the various devices specifically described may be varied in form without departure from my invention.

In the drawings, 1 is the aisle floor, and 2 is a berth-receiving pocket below the floor. Said pockets are constructed at one or both sides of the aisle in the drop section D of the car between the trucks and below the floor line thereof, as indicated in Fig. 1 by the dotted line f. For each pocket there is pro-

vided a pair of trap-doors respectively hinged at 4 near the upper edges of the ends of the pocket and adapted to fold one upon another to cover the pocket and form a part 5 of the car floor when the berths are not in use. In practice I construct a plurality of pockets beneath the car floor and along one or both sides of the car, these pockets being each of a depth sufficient to receive the superimposed 10 upper berth U and lower berth L when the berths are lowered into the pocket. Each pocket also contains, in its bottom portion under the berths, mechanism for actuating the berth-lifting and lowering devices that 15 are operatively supported, in part, by the trap-doors when raised. The construction of one berth section will suffice for a description of all the other sections, the construction being identical. The actuating mechanism 20 in each pocket is preferably covered by a false bottom 5 which is removable for access to the mechanism.

When the trap-doors of a given section are folded down one upon another to cover a 25 berth pocket they constitute a part of the flooring of the car and chairs may be placed upon them. When it is desired to use the berths, the chairs are removed, the trap-doors of the section raised into vertical position, and one or both berths raised into position of use. The chairs are then placed in the pockets out of the way, and, when all the parts are adjusted and the curtains hung, the berths are ready for use.

30 There are certain practical conditions to be met, in connection with the locking of the trap-doors when raised into vertical position, in order to secure a practically serviceable construction. When the trap-doors are 35 swung into vertical position, they must not pass that position, for, otherwise, in consequence of the strains due to the lurching of the car (or ship) there would be great danger of the doors becoming wrenched from 40 their hinges and so endangering life and limb. When raised into their proper vertical position, the doors must be locked rigidly and in such wise that they will not rattle, for otherwise there would be great danger 45 of a collapse of the structure and, if there was no such collapse, the rattling of the parts would prevent sleep. To meet these 50 conditions, I have devised door-arresting-locking and anti-rattling devices suitable for 55 the purpose in question and which may be made in various forms other than that now particularly described without departing from this feature of my invention, broadly considered. Fast on, and projecting inwardly 60 from an upper portion of the car side, I mount, in the path of each upwardly swinging trap-door above the space between each two adjacent pockets, an abutment 6 which is shown (Figs. 16, 17 and 18) in 65 duplicate form; that is, each abutment

serves to arrest each of two adjacent trap-doors of two adjacent sections or pockets. The upper part of each of these abutments is preferably extended upwardly into a garment hook, but this is a matter of convenience. Each abutment contains (in this instance on its under side) two bolt-receiving recesses 7, the outer, lower edges of the abutment adjacent to the recesses 7 being inwardly and downwardly inclined at 7^a (Fig. 70 75 16). When a trap-door is raised into its upright position, it bears against abutment 6 and is thereby prevented from being carried past that position. Consequently, the door cannot be wrenched from its hinges in 80 this raising movement of the trap-doors. Each trap-door is provided with a lock-bolt 8 beveled at its upper end and sliding in a bearing 9 fast in a recess of the trap-door. The lower end of each bolt 8 is provided 85 with a projecting pin 10 which plays in a slot 11 in an arm of the elbow-lever 12 pivoted to the trap-door at 13 and connected with a slide-bar 14 mounted in a lateral extension of the recess 15 in the trap-door. 90 Slide-bar 14 is provided with a shoulder 16. A spring 17 bears upwardly against the outer end of the elbow-lever to hold the bolt 8 in engagement with the recess 7 of the abutment. While the door is being raised to 95 its upright position, the beveled end of lock-bolt 8 strikes the incline 7^a and further movement causes the bolt to slide back against the stress of spring 17. As the bolt passes incline 7^a, it is forced upwardly by 100 the stress of spring 17 into the recess 7 so that the trap-door is thereby automatically locked in vertical position to the car side. The porter stands in the aisle while adjusting the parts and, as it is stronger and safer 105 to lock the trap-doors, at the inner edges thereof, to the car sides; and, as there is always danger of the car lurching while he is doing this work, it is important both for security and for quickness of operation that 110 the locking of the trap-doors in upright position should be automatic. It is furthermore desirable, for reasons of safety and to guard against ill-considered acts of malicious or ignorant occupants of the sections, 115 that the locking devices whereby the trap-doors are locked in their upright position should be under the sole care of the porter, and proof against manipulation by others than persons in charge of the car. The automatic locking mechanism just described is, 120 therefore, concealed in the recess 15 of the trap-door and its parts are not accessible except on removal of a cover-plate 19 for recess 15, (Fig. 2), and the trap-door is provided well toward the aisle edge thereof (so as to be in easy reach of the porter) with a fixture that contains a rotatable key-receiving stud 18 (see Fig. 17). The fixture 125 18^a, of which the rotatable stud 18 forms a 130

part, is covered by a plate 20 (see Fig. 6) provided with a hole through which the porter or other car attendant may insert a key to engage stud 18 provided with a projection 18^b which engages with shoulders 16 of slide-bar 14.

When it is desired to unlock the trap-door, a key is applied to stud 18 which is turned to bear against shoulder 16 and thereby 10 force slide-bar 14 in the direction of the car side so that the elbow-lever 12 presses downwardly against spring 17 and then pulls bolt 8 out of engagement with recess 7 in the abutment 6. This is done after the berths 15 are lowered; then the trap-door is manually lowered.

To prevent the upright trap-doors from rattling against the abutment, each trap-door is provided with a leaf-spring 21, the 20 free end of which bears against the abutment and prevents rattling. (See Figs. 16 and 18). The lower part of the abutment lies between a locking-bolt 8 and the free end of a spring 21 so that in this locked position any vibration of the upright door will 25 not cause rattling. Compactness of construction is desirable and, therefore, the duplex construction illustrated in Figs. 16 and 17 is desirable, one abutment serving for 30 each two adjacent trap-doors of two adjacent pockets or sections. This duplex arrangement is also desirable because, when the trap-doors are in their vertical position, there is a narrow space p' (Fig. 18) between 35 their opposed surfaces, and this space is available for receiving a vertical and portable auxiliary partition strip p (Fig. 16), which forms a vertical partition between the inner edge of an upright trap-door and the 40 opposed side wall of the car.

The hereinbefore described novel features may obviously be varied in form without departing from the substance of this first novel feature of my improvement.

45 For clear understanding of further novel features of my improvement, I will first briefly describe old and well-known berth-raising and lowering devices and their accessory mechanisms, it being understood that 50 any other suitable devices and operating mechanisms may be substituted therefor, so long as the substitutes are capable of co-operation with the hereinafter described novel features of my present invention.

55 Each trap-door for each pocket is provided, on its inner or under side, with four sheaves 25, two for each end of the upper berth, and two for each end of the lower berth (Figs. 6 and 10.) Each berth has 60 four cables 26 attached to it, two at one end and two at the other end (the attachments being made in the berth-end lugs 26^a, Figs. 5 and 7), and these cables run over the sheaves 25 and in grooves 27 formed in the 65 inner surface of each trap-door and ex-

tended down the adjacent end walls of the pockets, within which the cables are deflected into a more or less horizontal path by sheaves 28 (Fig. 11) in the lower part of the pocket. The lugs 26^a also run up and down in grooves 27, the side walls of which are vertical and prevent the berths from being moved sidewise. The cables for the upper berth lead to an upper winding-drum 29 and the cables for the lower berth lead to a lower winding-drum 30. These drums are of the same diameter, are superimposed and mounted on a vertical bearing 31 held in suitable framing mounted in the bottom of the pocket. The cables are guided from deflecting sheaves 28 to the appropriate winding-drums by means of guide sheaves 32 and 33 (Fig. 6). The upper winding-drum is provided with a peripheral gear 34. The lower winding-drum is provided with a peripheral gear 34^a (Figs. 12 and 13).

A gear 35 fast on a vertical shaft 36 which is provided with a thereon fixed sprocket wheel 37, engages with and drives gear 34 of the upper winding-drum. A similar gear 38, 90 fixed on a vertical shaft 39 having a thereon fixed sprocket wheel 40, engages with and drives the gear 34^a of the lower winding-drum. When gear 35 is rotated in either direction, the gear 34 of the upper winding-drum is thereby rotated, and when gear 38 is rotated in either direction, the gear 34^a of the lower winding-drum is rotated. By 95 these means, the berths of a section may be moved independently, one at a time.

100 Each winding-drum has four peripheral grooves for the four cables of each berth, the cables passing through apertures K (Fig. 13) in the outwardly extending portions K' of the retaining ring K² (see Fig. 12.) The retaining ring is supported concentrically and closely outside of the grooved peripheries of both winding-drums, by arms K⁴ which are primarily supported by the frame G between upper and under members of 110 which the central bearing 31 for the winding drums is mounted. The face of the retaining ring is so close to the circumferentially-grooved winding-drums that the cables cannot loosen upon the drums so as to clear the 115 grooves without coming into restraining contact with the retaining ring. With each peripheral winding-drum gear 34 and 34^a, there engages a spur gear t which is secured 120 on a rotatable arbor t' to which one end of a volute counterbalancing spring u is fast, the other end of the spring being fastened to a fixed pin u' outside of the spring containing casing and support J. The purpose of the 125 springs u is to counterbalance the weight of the berths and to keep the cables from undue slackening when the berths are brought into their fixed raised positions.

The two cables for each end of each berth are arranged substantially as indicated in 130

the drawings and both have their ends secured to the appropriate winding-drums, at the same circumferential point, whereby the turning of the drums in a given direction 5 winds or unwinds both of the cables equally and insures avoidance of a slackening of one cable while the other is taut.

The winding-drums and the immediately coöperating parts just described constitute 10 an actuating mechanism for the berth-raising and lowering devices that comprise the trap-doors, the sheaves carried thereby, the cables and the cable-deflecting and guiding sheaves.

15 For operating the upper winding-drum 29, by rotation of gear 35 on shaft 36, a sprocket chain 41 extends from the sprocket wheel 37 which is fast on the shaft 36 to an actuating device which comprises a sprocket 20 wheel 42 fast on a vertical shaft 43 which has bearings in a tubular casing 44 that extends upwardly through the aisle floor in which its upper end is fastened. The upper 25 end of shaft 43 is made polygonal at 43^a for the application of a hand-crank X whereby shaft 43 is rotated and the upper-winding drum actuated to wind up or unwind the cables connected therewith and to the upper berth.

30 For actuating the under winding-drum 30, a separate but an identical construction is used. From sprocket wheel 40 fast on shaft 39, a second sprocket chain 41 extends to another sprocket wheel 42 fast on another 35 shaft 43 in another tubular casing 44. By reference to Fig. 2, it will be seen that there are provided for each section two shafts 43, the polygonal upper ends 43^a of which are exposed in the aisle floor in front of each 40 section. These auxiliary actuating mechanisms (Figs. 14, 15 and 15^a) one for each berth in a section, constitute safety devices for operating the actuating mechanism of the berth-raising and lowering devices.

45 Each of these safety devices comprises clutch members and, generally stated, their purpose is not only to operate the therewith connected winding-drums but to insure automatic coupling of the clutch members and 50 thereby arrest movement of the berths, in case the crank X is accidentally released from engagement with a shaft 43 while it is being rotated to raise or lower a berth. It will be readily understood that when a car or ship 55 is lurching, the attendant may have difficulty in keeping the crank X in place on a shaft 43 and that, if the attendant were to lose control of a shaft 43, when a berth is being lowered or lifted, the weight or load of the 60 berth might result in its falling and in consequent injury to the occupants or to the structure or luggage. Therefore, some sort of a safety device for operating the actuating mechanism of the berth-raising and 65 lowering devices is desirable.

The safety device, now referred to, has been tested out in practice and its safety feature is briefly this: The upper end portion of tubular casing 44 is provided with the therein fixed collar 45, the inner periphery of which is provided with teeth. A screw-ring 46, of lesser internal diameter than the internal diameter of toothed-collar 45, is screwed into the upper end of casing 44 and projects inwardly beyond toothed-collar 45 so as to form an upper abutment 70 for a toothed-collar 47 that is fast on a vertical, slideable hub 48 loosely mounted within the chamber of the upper end of casing 44. Hub 48, at its lower end, has its diameter 75 reduced to form an abutment 49 for the helical spring 50 which is mounted between a shoulder 51 of shaft 43 and abutment 49 so as to press hub 48 normally upward against the inwardly projecting lower end 80 wall of screw-ring 46. When toothed-ring 47 intermeshes with the toothed-ring 45, the two rings are locked together and, as the hub 48 has a polygonal passage for and forms a close fit on the polygonal upper end 85 90 of shaft 43, said shaft is then and thereby prevented from rotation.

When crank X is applied to polygonal end 43^a of shaft 43, where it is exposed in the aisle floor, downward pressure of the crank, which is slideable endwise on shaft end 43^a, pushes on hub 48 and carries toothed-ring 47 95 downwardly, against the tension of spring 50, out of engagement with toothed-ring 45, as shown in Fig. 14. When the parts are in 100 this position, shaft 43 may be rotated in either direction.

So far as above described and, generally considered, the safety auxiliary actuating device is identical with that shown in said Patent 105 534,756. But it now contains a feature of my present improvement that is of material consequence in practice.

Heretofore, and as shown in said Patent 534,756, the lower ends of the teeth of ring 45 and the upper ends of teeth of ring 47 have been flat. Consequently, when control 110 of shaft 43 has been accidentally lost and hub 48, carrying its toothed-ring 47, moved upwardly by expansion of spring 50, it has happened that the flat upper ends of the teeth of ring 47 would be pressed by the spring strongly against the lower flat ends of the teeth of ring 45, so that the two sets of teeth would not instantly and automatically 115 interlock. The operator would then have to replace the crank, and bring the teeth of ring 47 into interlocking position with the teeth of ring 45. To overcome this and produce an automatic interlocking of the two sets of teeth referred to, I now make the lower ends of the upper teeth and the upper ends of the lower teeth laterally inclined, as indicated in Fig. 15^b. In the preferred construction the rings 45 and 47 containing the 120 125 130

teeth are preferably made of hardened steel, and in consequence of the lateral inclination of the opposed ends of the teeth, they will instantly and automatically interlock, when 5 the lower teeth are pressed upwardly by the expansion of spring 50, whether the operator has control of shaft 43 or not.

Having thus described a practically efficient berth-raising and lowering device, and 10 actuating mechanism therefor, and an improved safety device for operating the latter, I proceed to describe other features of my invention whereby safety, privacy and convenience are obtained.

15 Practical conditions of railway-car and ship-cabin construction and requirements, limit the depth of the pockets, and economy of space and compactness of construction require that the chairs for each section or room 20 be stowed away when the berths are made up. Therefore, it becomes important to provide the trap-doors with three sets of sockets for the therewith interlocking hooks carried by the two berths. This is a feature of my 25 present invention.

When one or more of the berths is raised into position for use, it is essential to lock the berths to the then vertical trap-doors, in such a strong and positive manner that the 30 trap-doors and berth or berths will be interlocked without any possibility of a collapse, and without a rattling connection. When so locked, the weight and load of each berth comes on the trap-doors and relieves the 35 cables from undue strain whereby their durability is increased and a more rigid connection of all the parts secured. It is important that the berths be so rigidly and securely locked in position for sleeping use 40 that they will keep their position under any and all circumstances, except, of course overwhelming destructive ones. Accordingly, three sets of metal sockets 60; 160 and 260 are securely mounted on the inner faces of 45 the trap-doors each set on one trap-door being opposite the corresponding set on the other trap-door. Sockets 60 receive the end hooks 61 of the lower berth, if and when both berths are used. Sockets 260 receive 50 the end hooks of the upper berth, if and when both berths are used. The intermediate sockets 160 receive the end hooks of the upper berth, when the lower berth is not in use. At such times, the lower berth 55 is secured in sockets 60. That is, when only one berth is to be used, in a section, it is the upper berth that is brought into service. It is then secured in place with its bottom contiguous to the upper surface of the lower 60 berth which is then fixed in its position of use, in order to make room for chairs and luggage in the pocket. Said hook-receiving sockets are all of identical construction and are interiorly chambered so as to extend 65 downwardly from their surface openings

through which the pivoted hooks 61, projecting in pairs from the berth ends, are entered, after the berths have been raised into position for the interlocking of the hooks 61 with said sockets, there being one hook near 70 one corner and another hook near the other corner of each berth end (Figs. 7, 8 and 9). Each hook is pivoted at 62, in a slot of a lower hinge-leaf 63 attached to the berth end. This hinge-leaf is connected by a 75 pintle 64 with a companion hinge-leaf 163 which projects above the berth and is adapted to swing from a horizontal to a vertical position and vice versa, for inserting and withdrawing a hook 61 into and out of an opposed socket 60; 160 or 260, as the case may be. Link 65 has its upper end pivoted at 66 to the upper hinge-leaf 163, while the lower end is pivoted at 67 to an eccentric swell of hook 61, laterally of hook 80 pivot 62. Pivot 66 is above the hinge-pintle 64. When the lower berth has been raised into its proper position for interlocking with the sockets 60, (the upper hinge-leaves 163 being then folded down at the upper 85 side of the berth, as shown in Fig. 2 and at the right-hand end of the lower berth in Fig. 3) the attendant turns the berth-flaps 164 attached to the upper hinge-leaves 163 at each end, of the lower berth, into their vertical position, (see Figs. 3 and 8), and thereby rocks the hook 61 of each hinge to which the flap is attached, into a socket 60 (see Fig. 8). The berth-flaps of the upper berth are indicated by 165. The construction of the 90 upper berth-flaps and therewith connected hinges, hooks and hook-actuating devices, are identical with those of the lower berth. So long as a berth end flap is in vertical 95 position, links 65, connecting the upper hinge-leaves with hooks 61, hold the hooks firmly in interlocking connection with the opposed sockets. When a berth-flap is turned into horizontal position, the hooks 61 connected with that flap are rocked on their 100 pivots so that their free ends are carried out of the sockets and back into the slots of the lower hinge-leaves where the hooks are 105 out of the way, and do not interfere with the upward and downward movement of the 110 berths. One or more of these hooks may be used at each berth end, and the flaps may be dispensed with if desired. In that case, each upper hinge-leaf would be retained for actuating a link 65. The greater the load 115 in a berth that is thus locked in position, the stronger is the interlock of the berth with the adjacent-trap-door.

To prevent the hooks from being forced upwardly and out of the sockets, upper hinge-leaves 163 are locked in vertical position, preferably by locking the berth-flaps to the trap-doors. Such locking may be effected in many different ways but is well accomplished by the following means: The inner 120

surface of each trap-door is oppositely provided with a lower projecting latch 68 and with an upper projecting latch 681 of identical construction. The location of the lower latch 68 is indicated in the left hand berth section shown in Fig. 2, while the location of the upper latch 681 (of identical construction) is indicated near the upper end of the vertically adjusted trap-door, in the right hand berth section shown in Fig. 2. Each latch (see Fig. 19) is pivoted at 69 in a recess in a trap-door and is backed up by a spring 70, which holds the latch outwardly from the inner surface of the trap-door when the latch is to be used. The latch is foldable into the recess. For engagement with each upper latch 681, the flaps 165 of the upper berth are provided with metal bushings 71, each having an opening through it and an interior shoulder 72. When an upper flap 165 is raised into vertical position, shoulder 72 passes over the hooked end 682 of the latch and engages automatically therewith to hold the flap upright and to lock hooks 61 in their sockets. When it is desired to unlock a flap, downward pressure on the projecting end of the latch (which is accessible to the attendant) releases it from the shoulder, and the flap may be turned down. Upper berth-flaps 165, when the upper berth is raised into its highest position of sleeping use, form part of the end partitions of a given section, their upper portions then extending above the upper ends of the upright trap-doors.

The upper berth-flaps are provided, toward their upper ends, with auxiliary latch-receiving bushings 171 (identical in construction and operation with bushings 71) which, when the upper berth is in its position for use as a "lower," engages with the latches 68. The lower berth-flaps 164 are similarly provided with internally-shouldered latch-receiving blocks 172 which engage with latches 68 when the lower berth is in its position of use.

The inner side of each trap-door is provided with a grooved cam-plate 73, one opposite the other. When the upper berth is raised to its position of use, its inner side will be about opposite an upper window sill W and contiguous portions of the car wall, between which and the berth side there is a very considerable space. To close this space, the opposite ends of the upper berth-end (see Fig. 5) are provided with openings 73^a, through which studs 74 project into the grooves of the cam-plates 73, entering the lower ends of the cam-grooves, before the upper berth reaches its position of rest. Each stud 73 is carried by a slide-bar 75, the inner end of which is attached to a spring 76 which in turn is attached to the berth at 77. Each slide-bar oppositely extends, toward the wall side of the berth, through a guide 78, and is

pivotedly connected with an arm 79 of a bracket 80 on the outer edge of a partition-forming flap 81 hinged at 82 to the wall side of the upper berth. The groove in cam-plate 73 has a throw sufficient, when the upper berth reaches its position of use, to turn flap 81 on its hinges, from its vertical position against the wall side of the upper berth (Fig. 6) into horizontal position, so that its free edge approximately reaches the window sill W and the thereto contiguous partitions of the car wall.

The width and contour of flap 81 may be varied at will to suit the corresponding configuration of the opposed car wall or window construction. The windows W¹ are for the lower berths; the windows W² for the upper berths. Partition-flaps 81 effectually separate the upper and lower berth spaces even when the lower windows extend above the upper berth, the enlargement 81^a extending between the side framing of the windows. When the upper berth is lowered, the operation of the actuating mechanism for flap 81 is such as to fold it against the wall side of the upper berth, as shown in Fig. 6.

It is desirable, when the car is used as a chair car, that the curtain rods for the berth should not project outwardly, because such projection would mar the interior effect of the car; and therefore each curtain rod 85 is mounted on slide arms 86, to slide endwise into socket spaces at 87 in the car roof. When the berths are made up, the curtain rods 85 are pulled out and curtains 88 (Fig. 4) hooked thereon in the usual manner. When the curtains are removed and the berths are to be lowered, the curtain rods are pushed back. The curtain rods are held back (to prevent rattling) by means of pivoted latches 100 on brackets 101 fast to the car wall, between the slide arms 86. The latches are pressed upwardly on their pivots 102 by springs 103, the upper side of the latches supporting and pressing the curtain rods, against abutting parts of the brackets, by the tension of springs 103. The upper parts of the brackets 101 may be formed into coat hooks as shown, if desired. Springs 103 yield when the rods are pulled out over them, but their upward pressure is sufficient to hold the rods from noisy vibration.

When the lower berth is in its position of use (see Fig. 7) there is a considerable space between the lower front corner of the berth 120 and the front upper edge of pocket 2. It is through this space that the chairs are moved into and out of the pockets which are ordinarily large enough to receive two chairs and some luggage. To cover this space when the berths are made up, and thereby prevent accidents to persons walking through the car, a boot-board of any suitable construction should be provided. As shown in Figs. 3 and 7 (but the boot-board construction is 130

not a feature invented by me) the under side of the lower berth is provided with guide-ways 91 extending transversely of the berth, at its opposite ends, and in this slides the boot-board 90 having hinged sections 92 and 93; the section 92 being always in the guides 91, and the boot-board 90 being hinged to the front edge thereof at 94 and adapted to hang downwardly to close said opening, and section 93 resting on the aisle floor to keep the boot-board 90 upright when in position for closing the opening, and to prevent the boot-board from vibrating when it is down. The boot-board and its sections are slid into guide-ways 91 when the boot-board is not required in use. This construction allows the middle section 90 to be pushed back at its lower side so as to form an angular space for boots and hand-bags beneath the front side of the lower berth and between the two trap-doors that form the end partitions of a section. Boots and luggage in this recess are not in the way of persons passing along the aisle.

25 When the curtain rods are pulled out they are in line with the front edges of the upright trap-doors, and it is desirable that curtain fastening members be mounted in the front part of the trap-doors in such wise as 30 not to project therefrom because any projections from the edges of the trap-doors would involve recesses in the flooring to receive the projections when the trap-doors are horizontal. Accordingly, I mount (Fig. 17) pivoted 35 latches 110 in the recesses 111 in the front edges of the trap-doors and provide for each latch a spring 112 that keeps the free end of the latch vertical in the recess. The outer edges of the curtains are provided with but- 40 ton-heads 113 that, when forced into the recesses, engage with the free ends of the latches which, being concealed, cannot catch on the clothing of the operator when he 45 raises and lowers the trap-doors, as would be the case if the fastening members carried by the doors projected therefrom.

When the sections are made up, it is convenient to have coat hooks on the upper front corners of the upright trap-doors. 50 Should such hooks be fixed on the trap-doors, spaces would have to be found in the car floor to receive them, when the trap-doors were horizontal. Consequently I provide each trap-door with a socket in its upper front corner, and provide therefor a garment hook having a right-angle base 121, the inner walls of the arms of which are flat to and fit on the flat upper end and flat front edge of a trap-door, an integral pin 122 ex- 55 tending from the base and fitting in the socket which is in the diagonal line of the door, while the pin 122 is in the diagonal line of the right-angled hook base. Such detachable hooks maintain their position 60 without rattling.

The ears or lugs 26^a of the berth ends move up and down in grooves, as stated, in the inner sides of the upright trap-doors and this also prevents sidewise movement of the berths. The relation of the inner or 70 wall sides of the berths to the inner edges of the trap-doors and to the opposed car-wall is such that a clear space is left between the inner sides of both berths and the opposed car-wall. In the case of the upper 75 berth, the aforesaid flap is used (as a horizontal partition) to fill in the space between the inner side of the upper berth and the sill W of the lower window and opposed 80 portions of the car wall; but, the construction of the flap actuating mechanism is such that it is possible to prevent the flap from being actuated. Blocks or wedges may be inserted, if desired, between springs 75 and the opposed end walls of the berth to prevent pins 74 from projecting beyond the 85 berth ends for engagement with cam-plate 73.

In the case of the lower berth, it is desirable to keep the space between its inner side and the opposed car wall open or clear, to 90 permit the free circulation of air all around the lower berth; and, when the side flap of the upper berth is not turned down, to permit free circulation of air all around both berths. In the case of the lower berth, however, it is very desirable that it should be 95 removed from contact with the heating pipes h and the pipe-screen h' (the latter being very generally used to conceal the pipes) that run along the inner side of the car wall 100 above the car floor, because, in case of such contact, the berth will become heated up and make it uncomfortable for the occupant of the lower berth. By having an open space between the inner side of the lower berth 105 and the car wall, this objectionable contact is obviated and free circulation secured for the lower berth. Heat rising from the pipes facilitates the circulation through the space between the inner side of the lower berth and 110 the opposed car-wall.

I do not herein make claims based either on the trap-door abutments 6; or, on the portable or detachable garment-hooks indicated in part by 121; or, on the non-rattling 115 curtain-rod lock designated in part by 101; or, on the berth-locking hinges designated in part by 163, because the same severally form subject-matters of my applications Serial No. 372,531; Serial No. 372,532; Serial 120 No. 372,533 and Serial No. 372,534, respectively, and each filed May 8, 1907.

What I claim is:

1. In a structure having a berth-receiving pocket below the floor, the combination of a 125 structural side-wall; a pair of trap-doors each hinged at an opposite end of the pocket and adapted to be swung into upright partition-forming position; berth-raising and lowering devices carried by each of said 130

trap-doors; an actuating mechanism for said devices; means for operating and locking, in a desired position, said actuating mechanism; a berth movable up and down between 5 said trap-doors when they are upright, the berth being attached to said raising and lowering devices; berth-locking members on the trap-doors; coöperating berth-locking members on the berth ends; and means for 10 locking the berth-locking members in interlocked position.

2. In a structure having a berth-receiving pocket below the floor, the combination of a structural side-wall; a pair of trap-doors 15 each hinged at an opposite end of the pocket and adapted to be swung into upright partition-forming position; independent sets of berth-raising and lowering devices carried by each of said trap-doors; independent actuating mechanisms for each set of said devices; independent means for operating and locking, in a desired position, each of said 20 actuating mechanisms; a lower and an upper berth each movable up and down between 25 said trap-doors when they are upright, one berth being attached to one set of said raising and lowering devices and the other berth being attached to the other set of said raising and lowering devices; a set of 30 berth-locking members on each trap-door for the lower berth; a set of berth-locking members on each trap-door for the upper berth; berth-locking members on the ends of the lower berth; berth-locking members on 35 the ends of the upper berth; means carried by the lower berth for locking its berth-locking members in interlocked position with the coöperating berth-locking members on the trap-doors; and means carried by the upper 40 berth for locking its berth-locking members in interlocked position with the coöperating berth-locking members on the trap-doors.

3. In a structure having a berth-receiving pocket below the floor, the combination of a 45 structural side-wall; a pair of trap-doors each hinged at an opposite end of the pocket and adapted to be swung into upright partition-forming position; berth-raising and lowering devices carried by each of said 50 trap-doors; an actuating mechanism for said devices; means for operating and locking, in a desired position, said actuating mechanism; a lower berth movable up and down between 55 said trap-doors when they are upright, said lower berth being attached to said raising and lowering devices; berth-locking members on the trap-doors; coöperating berth-locking members on the berth ends; means for locking the berth-locking 60 members in interlocked position; and means for preventing said lower berth from being moved sidewise; the inner side of said lower berth, when the berth is interlocked with the trap doors, being at a distance from the opposed structural wall.

4. In a structure having a berth-receiving pocket below the floor, the combination of a structural side-wall; a pair of trap-doors each hinged at an opposite end of the pocket and adapted to be swung into vertical partition-forming position; berth-raising and lowering devices carried by each of said trap-doors; an actuating mechanism for said devices; means for operating and locking, in a desired position, said actuating mechanism; an upper berth movable up and down between 70 said trap-doors when they are upright, said upper berth being attached to the said raising and lowering devices; berth-locking members on the trap-doors; coöperating berth-locking members on the berth ends; means for locking the berth-locking members in interlocked position; and, at each end of said upper berth, flaps attached to said means for locking the berth-locking 75 members, to manipulate them, and, when the flaps are in vertical position, to form end partitions of a section extending above the upper ends of the upright trap-doors.

5. In a structure having a berth-receiving pocket below the floor, the combination of a structural side-wall; a pair of trap-doors each hinged at an opposite end of the pocket and adapted to be swung into upright partition-forming position; berth-raising and 80 lowering devices carried by each of said trap-doors; an actuating mechanism for said devices; means for operating and locking, in a desired position, said actuating mechanism; a lower berth movable up and 85 down between said trap-doors when they are upright, the berth being attached to said raising and lowering devices; berth-locking members on the trap-doors; coöperating berth-locking members on the berth ends; means for locking the berth-locking 90 members in interlocked position and a transverse structure attached to and carried by said last-mentioned means whereby the latter are manipulated.

6. The combination of an upwardly-swingable, partition-forming trap-door for a berth-receiving pocket with a vertical, structural side-wall at an angle to a broad side of the trap-door; an abutment projecting 95 from the wall into the path of the trap-door when it is swung into vertical position, to arrest the trap-door on reaching that position; and a locking member carried by the trap-door and adapted to interlock with 100 said abutment.

7. The combination of an upwardly-swingable, partition-forming trap-door for a berth-receiving pocket with a vertical, structural side wall at an angle to a broad side of the trap-door; an abutment projecting from the wall into the path of the door when it is swung into vertical position, to arrest the door on reaching that position; a locking member carried by the trap-door 115 120 125 130

- and adapted to interlock with said abutment; and a spring mechanism carried by said door and, when the door is locked to the abutment, being interposed between the 5 abutment and door.
8. The combination of an upwardly-swingable, partition-forming trap-door for a berth-receiving pocket with a vertical, structural side wall at an angle to a broad 10 side of the trap-door; an abutment projecting from the wall into the path of the door when it is swung into vertical position, to arrest the door on reaching that position; means for locking the upright trap-door to 15 said side wall; and means to prevent the door from rattling against said abutment.
9. The combination of two upwardly-swingable, partition-forming trap-doors for two adjacent berth-receiving pockets with a 20 structural side-wall at an angle to the broad sides of the trap-doors; an abutment projecting from the wall into the path of said two trap-doors when they are swung into upright position, the said abutment serving 25 to arrest each of said trap-doors when it reaches vertical position; means carried by each trap-door to interlock with said abutment; and springs carried by each trap-door and adapted to engage said abutment when 30 the trap-doors are upright.
10. The combination of two adjacent trap-doors of two adjacent berth-receiving pockets, each trap-door being swingable into an upright position, with an abutment which 35 arrests their upward movement when brought into vertical position and then holds the opposed surfaces of said trap-doors at a distance apart to form a partition-receiving space; means for locking said trap-doors in 40 upright position; and a movable partition in said space.
11. The combination of a pair of upright partitions forming the ends of a section or room, with a structural side-wall parallel 45 with the inner edges of the partitions; an upper window in said wall; an upper berth raisable and lowerable between said partitions; means for locking the said upper berth opposite the lower part of said window; and a partition-forming flap carried 50 by said berth and movable into a substantially horizontal position between the wall side of said berth and the opposed structural wall.
- 55 12. The combination of upright partitions forming the end walls of a section or room, with a berth movable up and down between said partitions; a flap hinged to the inner

side of said berth; a structural wall parallel with the inner side of said berth; and means 60 for moving said flap from a vertical to a substantially horizontal position.

13. The combination of upright partitions forming the end walls of a section or room, with a berth raisable and lowerable 65 thereinbetween; means for locking the berth ends to the partition; and means for locking such berth-locking devices in interlocked position.

14. The combination of a structural side-wall with a hinged partition movable from a horizontal to a vertical position; and a key-operated locking mechanism for locking the partition when in vertical position to 70 said side wall, one member of said locking mechanism being in the side wall, and the key-operated member being carried by the partition.

15. In a structure having a berth-receiving pocket and a trap-door therefor which 80 is movable into upright position, the combination of a garment-hook-receiving socket in the edge of the trap-door, with a removable garment-hook having a tang adapted for entrance into said socket.

16. A trap-door having in its upper front corner a diagonal socket adapted for the reception of the tang of a hook.

17. A partition provided on its edge with a recess and a therein mounted curtain-fas- 90 tening member.

18. The combination of a pair of hinged, trap-doors forming end partitions of a room or section with a berth raisable and lowerable thereinbetween; a socket in each trap-door for reception of berth-locking members on the berth-ends; and a berth-locking member on each berth-end, said member comprising a pair of hinged leaves, a hook and a link that is pivoted at one end to one of said leaves and at its other end to the other of 100 said leaves.

19. The combination of a pair of partition-forming trap-doors with a berth provided with hinged end-flaps; flap-locking 105 members carried by the flaps; and co-operating flap-locking members carried by the trap-doors; said co-operating locking members serving when interlocked to hold the berth-flaps in upright position.

In testimony whereof I affix my signature in presence of two witnesses.

HENRY PEARSON.
